UNITED STATES PATENT OFFICE

157,570

RAILWAY BRAKE BEAM

Robert B. Cottrell, Chicago, Ill., assignor to
American Steel Foundries, Chicago, Ill., a cor-
poration of New Jersey

Application September 10, 1947, Serial No. 141,301

Term of patent 14 years

(Cl. D66—3)

To all whom it may concern:

Be it known that I, Robert B. Cottrell, a citizen of the United States, residing at Chicago, Illinois, have invented a new, original, and ornamental Design for a Railway Brake Beam, of which the following is a specification, reference being had to the accompanying drawings forming a part thereof, wherein:

Figure 1 is a top plan view of a brake beam embodying my design;

Figure 2 is an end view of the beam taken from the right, as shown in Figure 1;

Figure 3 is a front elevation of the beam;

Figure 4 is a perspective view of the beam looking from the top front side of the beam slightly

to the left of the transverse center line thereof;
and

Figure 5 is a rear elevation of the beam.

I claim:

The ornamental design for a railway brake beam, substantially as shown.

ROBERT B. COTTRELL.
